UNITED STATES PATENT OFFICE.

JONAS NORTHROP, OF HOPEDALE, MASSACHUSETTS, ASSIGNOR TO
DRAPER COMPANY, OF HOPEDALE, MASSACHUSETTS, A CORPO-
RATION OF MAINE.

FILLING-REPLENISHING LOOM.

SPECIFICATION forming part of Letters Patent No. 724,121, dated March 31, 1903.

Application filed January 5, 1903. Serial No. 137,925. (No model.)

To all whom it may concern:

Be it known that I, JONAS NORTHROP, a subject of the King of Great Britain, and a resident of Hopedale, county of Worcester, State 5 of Massachusetts, have invented an Improvement in Transferring Mechanism for Automatic Filling-Replenishing Looms, of which the following description, in connection with the accompanying drawings, is a specification, 10 like characters on the drawings representing like parts.

In looms provided with mechanism for transferring automatically a fresh supply of filling to the running-shuttle the filling-carrier, such as a bobbin or cop-skewer, is rapidly transferred from a hopper or feeder to the shuttle. The tip or head of the filling-carrier is engaged by a rocking arm or trans- 15 ferrer at such time, and United States Patent 20 No. 647,918 shows and describes means for positively holding or grasping the tip of the filling-carrier in order to cure certain defects in operation when the tip is not so held.

This invention has a similar object in view— 25 namely, to provide means for grasping firmly the tip of the bobbin or cop-skewer during transfer and to obviate a very common fault, the snapping of the tip down, so as to bring extra and undesirable tension on the taut 30 filling-thread leading from the filling-carrier to the hopper or feeder. Owing to the force of the blow and for other reasons the filling-carrier is often inclined, with its tip considerably below the bottom of the shuttle. 35 When the shuttle is picked out of the shuttle-box, the tip is of course snapped up into place, but meanwhile it has very probably broken its thread. Again, the filling-carriers sometimes get out of position laterally while 40 entering the shuttle, so that their tip ends will strike the sides of the shuttle.

My present invention prevents both of such faults, as the tip of the filling-carrier is positively grasped and held during transfer and 45 until the filling-carrier is properly positioned in the shuttle.

An important feature of my invention is the release of the tip before the transferrer begins its return movement to normal posi- 50 tion.

In former devices employing a positive grip for the tip the quick return of the transferrer sometimes will pull the filling-carrier up more or less out of the shuttle, notwithstanding the very rapid release of the tip. 55

In my present invention the release is governed positively, and it is effected surely and accurately before the transferrer begins its return movement.

The various novel features of my invention will be described hereinafter in the specification and particularly pointed out in the following claims. 60

Figure 1 is a cross-sectional view of a portion of a loom, taken between the end plates or disks of the feeder or hopper and illustrating one embodiment of my invention, the transferring mechanism being shown in normal position. Fig. 2 is a detail view showing the filling-carrier just inserted in the shuttle with the tip-grasping means released and the transferrer just ready to return to normal position. Fig. 3 is a detail view, in side elevation, of the transferrer on its transferring stroke and the tip-grasping means 65 just about to act on the tip of the filling-carrier. Fig. 4 is a view of the parts shown in Fig. 3 looking toward the left; and Fig. 5 is a top view, partly broken out, of the controller for the tip-grasping means. 70

The lay A³, having one of its shuttle-boxes slotted at the bottom for the passage of the ejected filling-carrier, the self-threading shuttle S, the hopper or filling-feeder F, the inner disk a' thereof being shown in Figs. 1 and 2, 75 the fixed stud f on the stand A⁷, and the trans- 80 ferrer f', mounted to rock thereon, may be and are all substantially as in United States Patent No. 664,790, dated December 25, 1900, the transferrer having a depending arm f⁸, 85 carrying a notched dog m¹⁵, to be engaged by a bunter C² on the lay when a change of filling is to be effected. As in said patent, the transferrer has a lateral arm 21 secured rigidly thereto, the outer end of the arm being 90 enlarged and downturned, as at j, and bifurcated or slotted, as at j^X, Fig. 4, the lower end of said part, which constitutes a jaw, being concaved at its rear edge at 5. Within the slot j^X is inserted the upper end of a relatively 95 100

movable jaw j' , fulerumed on a pin 4 and having its prong-like lower end concaved on its forward edge at 6 opposite to the concave portion 5 of the opposed jaw. A bow-shaped 5 piece of leather, rubber, or other resilient and preferably non-metallic material 10 is inserted between and secured to the concaved portions of the jaws, as clearly shown in the drawings, this bow-shaped piece tending to 10 separate or open the jaws and engaging the tip of the filling-carrier b when the jaws are closed. The upper end of the jaw j' is enlarged and extended forward above the top of the slotted jaw j , as at j^2 , and projects beyond 15 the front upright edge thereof, as shown in Figs. 1, 2, and 3, the weight of such enlargement acting as a counterbalance to hold the jaw j' open, this tendency being assisted by the resiliency of the bow-shaped piece 10. 20 In the Patent No. 647,918 referred to the arm f^6 , fixedly secured to the stud f , sustains a yieldingly-mounted tip-support; but herein I have dispensed with such tip-support and utilize the arm to sustain means for controlling the opening and closing of the jaws. A pin d , extended loosely through the arm, has secured to its inner end a short sleeve d' , enclosing a spring s^x , Fig. 5, surrounding the pin and fast at one end to the sleeve, the 25 other end of the spring being secured to the arm. On its opposite or outer end the pin has secured to it an elongated upturned cam c , having a curved edge c' , gradually rising to the high part c^x and then suddenly dropping to the low part c^2 . The spring s^x is so wound as to normally retain the cam in the position shown, with its depending tail c^8 against a stop f^7 on the arm f^6 . Normally the extension j^2 is just above the upper end of the 30 cam; but when a change of filling is effected the transerrer f' swings downward to engage the head b' of the filling-carrier, and the extension j^2 just about engages the cam c as the jaws j and j' straddle the tip, as shown in Fig. 3. 35 As the transerrer continues to descend the cam-face c' acts to quickly turn jaw j' on its fulerum 4 in the direction of arrow 2, Fig. 3, thereby closing the jaws and compressing the bow 10 upon the tip of the filling-carrier, firmly grasping it. The face c' is long enough to hold the jaws closed upon the tip until the filling-carrier is inserted in the shuttle, the lower or grasping ends of the jaws entering the shuttle. Just before the 40 transerrer has fully completed its active or transferring movement, however, the extension j^2 passes off the high point c^x of the cam and drops into relative normal position when opposite the low part c^2 of the cam, the 45 weight of the extension and the bow 10 immediately opening the jaws and freeing the tip, as in Fig. 2. The tip is thus freed before the transerrer begins its retrograde movement to normal position, and hence there 50 is no possibility of the tip being lifted by such movement. As the transerrer rises the end of the extension j^2 wipes over the cam

edge and swings the cam on its fulerum-pin d against the action of the spring, the cam thereby yielding to permit the return of the extension with the transerrer, and, as will be seen from Fig. 1, the parts are then in readiness for the next transfer of filling. 55

The opening and closing of the jaws is entirely independent of the filling-carrier, and the controlling device or cam is also mounted independent of the transerrer, as will be manifest from the foregoing. 75

My invention is not restricted to the precise construction and arrangement herein shown and described, as the same may be modified or changed in different particulars by those skilled in the art without departing from the spirit and scope of my invention. 80

Having fully described my invention, what I claim as new, and desire to secure by Letters Patent, is—

1. In a loom provided with automatic filling-supplying mechanism, a transerrer, means mounted thereon to grasp the tip of a filling-carrier, and a controller independent of the transerrer to cause said means to grasp and release the tip automatically. 90

2. In a loom provided with automatic filling-supplying mechanism, a transerrer having jaws to engage and hold the tip of a filling-carrier during transfer, and means independent of the transerrer and the filling-carrier to effect automatically the closing and opening of the jaws. 95

3. In a loom provided with automatic filling-supplying mechanism, a transerrer, means mounted thereon to grasp the tip of a filling-carrier, and a controlling-cam mounted independently of the transerrer, to coöperate with and cause said means to grasp and release the tip automatically. 105

4. In a loom provided with automatic filling-supplying mechanism, a transerrer, means mounted thereon to grasp the tip of a filling-carrier, and a controller to cause said means to grasp the tip during transfer and to release the tip as the transferring movement of the transerrer is completed. 110

5. In a loom provided with automatic filling-supplying mechanism, a transerrer having jaws to engage and hold the tip of a filling-carrier during transfer, and a controller to close the jaws automatically as transfer begins and to effect opening of the jaws and release of the tip prior to return movement of the transerrer. 115

6. In a loom provided with automatic filling-supplying mechanism, a transerrer having jaws to engage and hold the tip of a filling-carrier during transfer, and means mounted independently of the transerrer to close the jaws automatically during transfer and to effect their opening to release the tip as the transerrer completes its transferring movement. 125

7. In a loom provided with a feeder to hold a supply of filling-carriers, a rocking transerrer having a fixed tip-holding jaw and a co-

operating, relatively movable jaw, and a controller mounted independently of the trans-
ferrer to engage and close the movable jaw
upon the tip of a filling-carrier to be trans-
ferred and to retain it closed during transfer,
and to effect opening of the movable jaw be-
fore the transerrer begins its return move-
ment.

8. In a loom provided with automatic filling-
supplying mechanism, a transerrer having
jaws to engage and hold the tip of a filling-
carrier during transfer, and a cam mounted
independently of the transerrer, to close the
jaws automatically at the beginning of trans-
ferring movement of the transerrer and to ef-
fect their opening as such movement ceases,

the closing and opening of the jaws being ef-
fected independently of the filling-carrier.

9. A transerrer for automatic looms, hav-
ing tip-grasping jaws mounted upon it, and
means independent of the transerrer and op-
erating independently of the filling-carrier to
close the jaws upon the tip of the latter dur-
ing transfer and to open them prior to retrac-
tion of the transerrer.

In testimony whereof I have signed my
name to this specification in the presence of
two subscribing witnesses.

JONAS NORTHROP.
